UNITED STATES PATENT OFFICE.

LOTTIE P. LIGON, OF ROANOKE, VIRGINIA.

CYLINDER-COCK.

1,323,076.

Specification of Letters Patent. Patented Nov. 25, 1919.

Application filed February 26, 1919. Serial No. 279,384.

To all whom it may concern:

Be it known that I, LOTTIE P. LIGON, a citizen of the United States, and resident of Roanoke, in the county of Roanoke and 5 State of Virginia, have invented certain new and useful Improvements in Cylinder-Cocks, of which the following is a specification.

The present invention relates to cylinder 10 cocks, such as are used for draining the cylinders of locomotives and the like, and the object of the invention is to provide a cylinder cup comprising a valve and body or casing of novel construction, and novel operating 15 means for the valve, whereby the device is thoroughly practical and efficient in use.

A further object is the provision of such a device which will lock the valve when closed, so as to prevent the inlet of air to 20 the cylinder and also prevent the valve from hammering on the seat when the engine is drifting.

It is also the object to provide a cylinder 25 cock having the features above noted, and which at the same time is comparatively simple and inexpensive in construction, and substantial and durable so as not to be apt to get out of order.

With the foregoing and other objects in 30 view which will be apparent as the description proceeds, the invention resides in the construction and arrangement of parts hereinafter described and claimed, it being understood that changes can be made within 35 the scope of what is claimed without departing from the spirit of the invention.

The invention is illustrated in the accompanying drawing, wherein:—

Figure 1 is a vertical median section of 40 the device, the operating bar or slide being shown in elevation and being partly broken away, with the valve seated.

Fig. 2 is a similar view showing the valve unseated.

Fig. 3 is a bottom plan view of the valve 45 and its casing or body.

The body or casing 1 of the cylinder cock is tubular and disposed vertical as usual, the upper end of the body or casing 1 being 50 screw threaded, as at 2, or otherwise formed for attachment to the cylinder, in order that the condensation will drain from the cylinder down into the body 1. This body 1 is provided between its upper and lower ends 55 with an interior annular flange 3 having an upper beveled valve seat 4, and the body

has an enlarged chamber 5 below the flange 3 and a central vertical bore 6 extending from the chamber 5 to the lower end of the body to provide a guide for the valve. The 60 body 1 is provided at one side with a longitudinal or vertical slot 7 extending from the chamber 5 to the lower end of the body, while at the opposite side, the body 1 has a similarly extending slot 8 which terminates short of the lower end of the body, 65 said slots being in diametrical alinement.

The valve comprises a vertical cylindrical shank or stem 9 movable loosely in the bore or guide 6, and provided at its upper end 70 with a neck 10 projecting through the opening surrounded by the valve seat 4, said neck 10 having a valve head 11 at its upper end above the seat. The lower surface of the head 11 is beveled to fit the seat 4 and 75 provide a tight fit, as seen in Fig. 1. The shank or stem 9 has a diametrical slot 12 between and registering with the slots 7 and 8 for the passage of the operating slide or 80 bar.

The operating means includes a bar or slide 13 projecting through the slots 7, 8 and 12 with its lower edge seating on the lower end of the slot 8 to support said bar. The upper edge of the bar 13 is cut away 85 as at 14, to allow the valve to drop down and seat, as seen in Fig. 1, and one end of the cut away portion or recess 14 is inclined to provide a cam 15 for lifting the valve. Thus, when the bar or slide 13 is moved 90 toward the left as viewed in the drawing, the cam 15 in contacting with the valve will lift it to the position shown in Fig. 2, thus permitting the water to drain from the cylinder through the valve seat opening, 95 chamber 5 and slot 7 which forms a discharge outlet. At that end of the cut away portion or recess 14 opposite to the cam 15, there is an upstanding lug or stop 16 that moves snugly under the upper end of the 100 slot 7 when the bar or slide 13 is returned, thus preventing said bar or slide from lifting or raising when the cut away portion 14 moves under the upper end of the slot 8.

In order to lock the valve on its seat, the bar 105 or slide 13 is provided with a widened or depending portion or lip 17 below the lug 16 and cut away portion or recess 14 and movable snugly over the lower end of the slot 12 as seen in Fig. 1, when the valve is 110 seated, thereby holding the valve on its seat, and preventing the valve from being drawn

open by the suction created in the cylinder. This will prevent the inlet of air into the cylinder, and will also prevent the valve from hammering on its seat when the engine is drifting.

The bar or slide 15 can be bolted or otherwise fastened to an operating bar 18 for connecting the slide 15 with the slide of another cylinder cock when they are used in pairs and any suitable means can be used for operating the slides, according to the prevailing practice.

Having thus described the invention, what is claimed as new is:—

15. A cylinder cock comprising a tubular body having a valve seat and slots below said seat, a valve having a shank slidable

in said body below the seat and having a valve head at its upper end seatable on said seat, said shank having a slot, and a slide 20 extending through all said slots and having a recess in its upper edge with a cam at one end of the recess to lift the valve and an upstanding lug at the opposite end of the recess to move snugly under the upper end of the corresponding slot in the body, said slide having a depending portion below said recess to move into the slot of said shank close to the lower end thereof when said lug moves into the body for holding 30 the valve head on the seat.

In testimony whereof I hereunto set my hand.

LOTTIE P. LIGON.
